UNITED STATES PATENT OFFICE.

KARL ZAHN AND PAUL OCHWAT, OF HOCHST-ON-THE-MAIN, GERMANY, ASSIGNORS TO GRASSELLI DYESTUFF CORPORATION, OF NEW YORK, N. Y., A CORPORATION OF DELAWARE.

PROCESS OF PREPARING DERIVATIVES OF DIBENZANTHONYL.

No Drawing. Application filed December 28, 1926, Serial No. 157,611, and in Germany December 30, 1926.

We have found that by heating the ethers of Bz1-iodo-Bz2-hydroxybenzanthrones with copper powder in an indifferent solvent, the hitherto unknown diethers of Bz2-Bz2'-dihydroxy-Bz1-Bz1'-dibenzanthryns are obtained, which can be converted by the action of alkaline condensing agents into valuable dyestuffs of the dibenzanthrone series. The last mentioned reaction takes place according to the general equation:

wherein X stands for an alkyl residue.

The following example serves to illustrate our invention, but it is not intended to limit it thereto, all parts being by weight:

10 parts of Bz1-iodo-Bz2-methoxybenzanthrone of the melting point 248° C. which is easily obtainable by one of the known methods, are heated to boiling for 5 hours in 50 parts of nitrobenzene with 10 parts of copper powder, and the hot solution is then filtered. After the filtrate has cooled, the separated product is drawn off by suction, washed and dried. The Bz2-Bz2'-dimethoxy-Bz1-Bz1'-dibenzanthryl thus prepared forms brown needles of the melting point 387-390° C. and is soluble in concentrated sulfuric acid to a claret-red solution.

We claim:

1. As new products, compounds of the 50 general formula:

wherein X stands for an alkyl residue.

2. As a new product, a compound of the 75 general formula:

which forms brown needles melting at 387-390° C. and dissolves in concentrated sulfuric acid to a claret-red solution.

3. In a process for preparing derivatives of dibenzanthronyl the step comprising heating an ether of Bz1-iodo-Bz2-hydroxybenzanthrone with copper powder in an indifferent solvent.

4. In a process for preparing vat dyestuffs of the dibenzanthrone series the step com-

prising heating a Bz1-iodo-Bz2-methoxybenzanthrone with copper powder in an indifferent solvent.

In testimony whereof, we affix our signatures.

KARL ZAHN.
PAUL OCHWAT.

CERTIFICATE OF CORRECTION.

Patent No. 1,675,014.

Granted June 26, 1928, to

KARL ZAHN ET AL.

It is hereby certified that error appears in the printed specification of the above numbered patent requiring correction as follows: Page 2, lines 6 and 7, claim 4, strike out the words "vat dyestuffs of the dibenzanthrone series" and insert instead "derivatives of dibenzanthronyl"; and that the said Letters Patent should be read with this correction therein that the same may conform to the record of the case in the Patent Office.

Signed and sealed this 7th day of August, A. D. 1928.

(Seal)

M. J. Moore,
Acting Commissioner of Patents.

CERTIFICATE OF CORRECTION.

Patent No. 1,675,014.

Granted June 26, 1928, to

KARL ZAHN ET AL.

It is hereby certified that error appears in the printed specification of the above numbered patent requiring correction as follows: Page 1, claim 2, in the formula the upper radical "O C H sub 3" should be connected by its bond to the lower right hand corner of the adjacent ring and the lower radical "O C H sub 3" should be connected by its bond to the upper right corner of the adjacent ring, so that both of the radicals will occupy the relative positions of the radicals "O X" in claim 1; and that the said Letters Patent should be read with this correction therein that the same may conform to the record of the case in the Patent Office.

Signed and sealed this 11th day of September, A. D. 1928.
